UNITED STATES PATENT OFFICE.

GEORGE S. HILL AND DANIEL A. HITCHCOCK, OF HAVERHILL, MASSACHUSETTS, ASSIGNORS TO JOHN J. SULLIVAN, OF IPSWICH, MASSACHUSETTS.

BUTTONHOLE-SEWING MACHINE.

SPECIFICATION forming part of Letters Patent No. 642,122, dated January 30, 1900.

Application filed January 17, 1898. Serial No. 666,848. (No model.)

To all whom it may concern:

Be it known that we, GEORGE S. HILL and DANIEL A. HITCHCOCK, of Haverhill, in the county of Essex and State of Massachusetts, 5 have invented certain new and useful Improvements in Buttonhole-Sewing Machines, of which the following is a specification.

This invention relates to an improvement in buttonhole-sewing machines; and it consists in the novel features of construction and relative arrangement of parts hereinafter fully described in the specification, clearly illustrated in the drawings, and particularly pointed out in the claims.

Reference is to be had to the accompanying seven sheets of drawings, forming a part of this application, in which like characters indicate like parts wherever they occur.

In the drawings, Figure 1 represents in side 20 elevation a machine embodying our invention. Fig. 2 represents a top plan view of the mechanism below the bed-plate, the latter being broken away. Fig. 3 represents a cross-sectional view on the line 33 of Fig. 2, looking 25 in the direction of the arrow. Fig. 4 represents a front end elevation of the machine. Fig. 5 represents a rear end elevation of the machine. Fig. 6 represents a side elevation 30 of the stop movement for the sewing mechanism. Fig. 7 represents a vertical sectional view on the line 77 of Fig. 5. Fig. 8 represents a cross-sectional view on the line 88 of Fig. 6. Fig. 9 represents a top plan view of the intermittent gears and locks for rotating 35 and locking the needle-bar and turret, the locks being shown in engagement. Fig. 10 is a like view showing the gears in engagement. Fig. 11 represents a detail perspective view of the starting mechanism. Fig. 12 represents 40 a detail perspective view of the release rock-shaft for the work-clamp toggles. Fig. 13 represents a vertical sectional view of the turret with its sewing mechanism, also the upper needle, the knife, and knife-block. Fig. 14 represents a top plan view of the 45 turret and parts carried thereby. Fig. 15 represents a detail view showing in front elevation the looper mechanism and a section of the turret. Fig. 16 represents a detail view of

the throat-plate for handling the cord, the 50 work being shown in dotted lines, it being understood that the work rests on top of the work-plate. Fig. 17 represents a cross-sectional view thereof. Fig. 18 is a view similar to Fig. 16, showing the work removed and the 55 cord drawn clear for the next stitch. Fig. 19 represents a detail perspective view of the sewing mechanism, showing the under needle passing through the loop of the upper needle held by the looper. Fig. 20 represents a like 60 view of the same parts, showing the upper needle passing through the loop of the under needle. Fig. 21 is a like view of the same parts, showing the looper passing through the loop of the upper needle. Fig. 22 represents 65 in top plan view the relative arrangement of the work-holding arms and the spreading-pin.

Referring to the drawings, in the embodiment of our invention therein shown and selected by us for the purpose of illustration the base A, bed-plate A', and the overhanging arm A² may be of any preferred construction, our invention not relating to these parts, but to the hereinafter-described mechanism supported thereby.

a represents a shaft mounted in suitable bearings on the under side of the bed-plate in the rear of the machine. This shaft we term for convenience the "rear" shaft.

a' represents a pulley fast upon the end of the shaft a and arranged to be driven by a belt a² from another wheel. (Not shown.)

In the present embodiment of our machine the wheel a' is designed to run continuously 85 and carries upon its inner side a spiral cam a³, (see Figs. 2, 4, and 5,) arranged to engage for a predetermined length of time a roll a⁴ on the end of the sliding stud a⁵. This stud is slidingly arranged in the horizontal arm a⁶ 90 of a bell-crank lever a⁶, said lever being pivoted at its angle upon a pin a⁷, carried by a bracket a⁸ on the lower side of the bed-plate. A helical spring a⁹ is arranged upon the stud a⁵ between the inner face of the arm a⁶ and a cap a¹⁰, screwed upon the inner end of the stud, whereby the roll is yieldingly held in a 95 plane inside of the plane of a spiral cam a³.

and therefore out of engagement with said cam except when thrown into engagement by means hereinafter described.

a^{11} represents a crown-cam loosely mounted on the shaft a and secured to and arranged to turn with the wheel a' . Preferably this crown-cam a^{11} is formed on an extended hub of the wheel a' .

a^{12} represents a disk fast on the shaft a , provided with a lug a^{13} .

a^{14} represents a clutch member pivoted at one end to the lug a^{13} .

a^{15} represents a spring arranged between the disk a^{12} and clutch member and arranged to throw the free end of the clutch member outward and its pin a^{16} into the slot a^{17} in the web of the crown-cam a^{11} when the lower end of the clutch member is released from the cam-track a^{18} on the lower arm a^{61} of the bell-crank a^6 . This cam-track is arranged to engage at a predetermined time the free end of the clutch member, and as the clutch member continues to revolve the engagement of its free end with this cam-track will withdraw the pin a^{16} from the slot a^{17} .

a^{19} represents a bell-crank lever pivoted to a bracket at the top of the bed-plate. One arm of this lever is above the bed-plate, while the vertical arm of the lever is connected at its lower end to a sliding rod a^{20} . (See Figs. 1 and 2.) The free end of the rod a^{20} is arranged to engage the cap a^{19} . The operator by depressing the horizontal arm of the lever a^{19} can thus throw the roll a^4 into engagement with the cam a^3 . As the cam continues to revolve it depresses the stud and at the same time the horizontal arm a^{61} sufficiently to draw this arm out of engagement with the free end of the clutch member a^{14} , thereby permitting the engagement of the pin a^{16} with the slot a^{17} , and thereby clutching the shaft a with the wheel a' , the clutch remaining in engagement until its free end engages the cam-track a^{18} , as heretofore described. The downward movement of the arm a^{61} causes an inward movement of the vertical arm of the bell-crank, the upper end of which is arranged to engage an arm of the lever a^{21} and force it in the direction of the arrow in Fig.

50 11. The lever a^{21} is pivoted to the bed-plate, as at a^{22} , and has its opposite end arranged to engage the knuckles of the toggles of the work-clamp hereinafter described. (See Figs. 2 and 4.)

55 The shaft a is provided with an eccentric a^{23} , upon which an eccentric-strap a^{24} is arranged, having a pitman a^{25} connecting said strap with the free end of the crank-arm a^{26} . The opposite end of the crank-arm a^{26} is fast 60 upon a shaft a^{27} , mounted in suitable bearings in the overhanging arm.

a^{28} represents a crank-arm secured to the front end of the shaft a^{27} and having its free end pivoted to one end of an arm a^{29} , the opposite end of which is pivoted to a collar a^{30} , fast upon the cutter-bar a^{31} . (See Fig. 4.) This cutter-bar is arranged to slide in brack-

ets a^{32} a^{33} , extending from the front end of the overhanging arm. The collar a^{30} is provided with a pin a^{34} , arranged to slide in a suitable hole in the lower bracket a^{33} , in order to guide the cutter-bar and prevent the latter from twisting.

a^{35} represents a knife carried by the lower end of the cutter-bar, formed to cut a button-hole or slit in the cloth or fabric. This cutter-bar is shown as arranged to move at an angle to the needle, in order that one end of the slot made by the knife may be directly under or close to the plane occupied by the path of the needle, so that the buttonhole will be cut in position to be stitched without further manipulation of the cloth or fabric. This inclined position of the cutter-bar to the needle in addition to enabling the knife to have a forward as well as a downward movement to properly position and cut the slit also enables the knife and bar after the cutting operation to be readily drawn upward and away from the path of the needle.

The operation of the mechanism thus far described is as follows: The operator depresses the horizontal arm of the starting-lever a^{19} , thereby forcing the roll a^4 into engagement with the spiral cam on the continuously-running wheel a' . As the latter continues to revolve the roll and pin and also the horizontal arm are depressed, first causing the movement of the lever a^{21} to straighten the toggles of the work-clamp and clamp the work. Immediately thereafter the clutch member a^{14} is released and the wheel a' locked to the shaft a , thereby causing the latter to revolve. This movement of the shaft a imparts one complete reciprocation to the cutter-bar a^{31} , causing the latter to descend to cut the work and to return to its initial position. The parts are so timed that as soon as this movement of the cutter-bar is completed the free end of the clutch member a^{14} engages the cam-track a^{18} and its pin a^{16} is withdrawn from engagement with the aperture a^{17} in the web of the crown-cam to automatically stop the shaft a .

a^{40} represents a path-cam fast on the shaft a .

a^{41} represents a lever pivoted at one end to a suitable bracket on the framework and at its free end to a reciprocating rod a^{42} .

a^{43} represents a roll on the lever a^{41} and arranged in the path of the cam a^{40} . The free end of the rod a^{42} (see Fig. 3) is arranged to engage a lug a^{44} , pivoted to a bail a^{45} , that in turn is pivoted on the turret, hereinafter described, at a^{68} , said bail extending across the turret and having its ends bent downward for that purpose. (See Figs. 13 and 14.) To this bail a^{45} is secured a cutter-block a^{46} and a throat-plate a^{47} . A spring a^{48} (see Fig. 2) serves to yieldingly hold the bail, cutter-block, and throat-plate normally in the position shown in Fig. 3. When, however, the shaft a is rotated to cut a buttonhole, as hereinafter described, simultaneously with the

motion of the cutter bar, the rod a^{12} is thrown forward by the cam a^{10} , roll a^{13} , and lever a^{14} to lock the bail a^{15} and throw the cutter-block into the position shown in Fig. 13 to provide for the engagement of the knife with the cutter-block and insure the proper and accurate cutting of the buttonhole. The continued rotation of the shaft a withdraws both the cutter-bar and the rod a^{12} into position shown in Fig. 3, the spring a^{18} returning the bail to the position shown in Fig. 3 and the throat-plate a^{17} to the position therein shown ready for the stitching operation.

The throat-plate a^{17} is formed with the usual hole t^{21} for the passage of the needle and also with an undercut annular rib t^{22} , around which the cord which is employed to strengthen the edges of the buttonhole wraps as the needle-turret is rotated. (See Fig. 16.) This projection t^{22} is slotted, as at t^{23} , in order to let the cord be disengaged when the buttonhole is completed, as shown in Fig. 18.

b represents a lever pivoted midway its ends to the under side of the bed-plate, one end of this lever (see Fig. 11) being arranged to be engaged by the crown-cam a^{11} immediately after the clutch member a^{14} has been disengaged from the web thereof. The engagement of the said crown-cam with the roll b' of the lever b throws inward the opposite end b^2 of said lever (see Fig. 2) and through the sliding bar b^3 , to which said end b^2 is connected, causes the outer end of the bar b^3 to slide the stop mechanism. (Shown in Figs. 6, 7, and 8.) The inward movement of the end b^2 of the lever removes the plunger of the stop mechanism from the notched hub of the fast pulley and at the same time throws the belt b^{31} from the loose pulley b^{41} to the fast pulley b^{51} , thereby starting the shaft b^5 , by which the sewing mechanism is driven. The belt b^{31} is connected to and driven by a wheel, (not shown,) it being understood that this belt as well as the belt on the wheel a' are driven continuously, and, further, that the shaft b^5 is not started until after the stopping of the shaft a or substantially at that time. A path-cam b^6 on the shaft b serves to give motion to the take-up arm b^7 .

b^8 is a lever pivoted midway its ends to the under side of the bed-plate and of which one end is arranged to be engaged by a wiper b^{10} on one of the disks hereinafter described. The opposite end of this lever is formed with a dog b^{11} , arranged to engage an aperture in the bar b^3 when the latter is moved inward by the lever end b^2 in order to hold the parts in the position to which they are thrown by this arm. The inner end of the bar b^3 is cored out, and in this core is arranged a helical spring b^{12} , the said spring bearing at one end against the inner wall of the core and its opposite end against a fixed abutment b^{13} .

The parts are so arranged and timed that after the completion of the stitching operation and just before the unclamping of the work the wiper b^{10} engages the arm b^8 , there-

by releasing the dog b^{11} from the bar b^3 , permitting the spring b^{12} to force the bar outward to throw the belt b^{31} to the loose pulley b^{41} 70 and the plunger of the stop mechanism into engagement with the cam on the fast pulley, hereinafter described.

b^{14} represents a rock-shaft mounted in suitable bearings in the bed of the machine. 75 This rock-shaft is formed with a depending arm b^{15} , arranged to be engaged by a wiper b^{16} , carried by the path-cam b^6 , (see Fig. 12,) and it carries an arm b^{17} , arranged to engage a complementary arm b^{18} , connected to the 80 toggles of the work-clamp. In order to keep the arm b^{15} in the path of the wiper and the arm b^{17} normally in the inoperative position, a spring (not shown) is connected to the arm b^{15} and to the bed-plate. The parts are so 85 timed that the wiper b^{16} engages the arm b^{15} to rock the shaft and open the work-clamp just after the engagement of the wiper b^{10} with the arm b^8 to throw the belt b^5 to the pulley b^{41} and slide the stop mechanism to its 90 operative position.

From the foregoing it will be seen that the depression of the hand-lever a^{19} engages the roll a^4 with the spiral cam and that thereafter the several operations of the machine are 95 automatic in the order named, the first movement being to clamp the work, immediately after which the knife mechanism is operated. At the completion of these two steps the shaft a is automatically stopped and the shaft b^5 is 100 automatically started, the latter being automatically started after the completion of the clamping and cutting operation and automatically stopped after the completion of the stitching operation. 105

Referring to Fig. 1, b^{19} and b^{20} represent the disks, forming members of the tension device for the needle-thread. b^{21} represents a rod passing down through both disks into the arm A^2 . b^{23} represents a helical spring arranged on the rod b^{21} between the disk b^{20} and a nut b^{24} . By this construction constant tension is maintained on the thread during the stitching operation. b^{25} represents an arm, one end of which is forked to engage a complementary groove of the outer end of the rock-shaft b^{14} . The opposite end of this arm is secured to the sliding stop mechanism, whereby the rod b^{21} slides in unison with the bar b^3 . When the arm b^2 slides the bar b^3 inward to start the shaft b^5 , the arm b^{15} is slid to the left in Fig. 12 a sufficient distance to clear the wiper b^{16} . When, however, the bar b^3 is released and thrown to the right in Fig. 2 by means of the spring b^{12} , the arm b^{15} 115 is moved into the path of the wiper b^{16} . A loop b^{26} in Fig. 2 extends from the stop mechanism around the belt b^{31} , whereby the said belt is moved to and from the fast pulley b^{51} by the inward and downward motion 120 of the bar b^3 . When the belt is shifted from the tight to the loose pulley, some provision is necessary for bringing the sewing mechanism to rest at the proper point without 125 130

shock. To accomplish this result, we have provided the means shown in Figs. 1, 2, and 5 and in detail in Figs. 6, 7, and 8. Upon the shaft b^5 and in close proximity to the 5 fast pulley b^{51} is mounted a sliding box or support c , to which the outer end of the bar b^8 is secured and by which the box is slid, the bar serving not only to keep the box in position, but also to move the latter. This box is 10 formed with an annular chamber c' , which is arranged with a helical spring c^2 , the spring being confined at either end by pins c^3 . c^4 represents a sleeve loosely mounted on a hub of the box c , provided with an upwardly-extending arm c^5 . c^6 represents lugs formed on either side of said arm and arranged to engage the spring c^2 , as shown in Fig. 8. The arm c^5 extends upward through a suitably-formed slot in the top of the box and after it 20 leaves the box is extended at an angle toward the fast pulley b^{51} . (See Fig. 6.) This extension c^7 is hollowed out to form a chamber, in which a plunger c^8 works. (See Fig. 7.) The plunger is formed with a pin c^9 , arranged in 25 a complementary slot c^{10} , in order to prevent a twisting motion of the plunger. The plunger c^8 at its upper end is cored, and in this core portion is arranged a helical spring c^{11} . c^{12} represents a cap screwed to the upper end of 30 the extension c^7 and carrying a rod c^{13} , arranged within the helical spring c^{11} , the latter bearing at one end against the lower portion of the chamber in the rod c^8 and its upper end against the cap c^{12} , as shown in Fig. 7. 35 By this construction the plunger c^8 is spring-pressed toward the shaft b^5 , the tension being regulated by means of a cap c^{12} .

The operation of the construction above described is as follows: Referring to Fig. 6, in 40 which the parts are represented as they are situated during the stitching operation, the end of the plunger c^8 being clear of the cam c^{14} , formed on the tight pulley b^{51} , at the completion of the stitching operation heretofore referred to the bolt b^8 is slid to the right in Fig. 2. This movement also carries the sliding box to the right in said figure and also in Fig. 6. This movement of the box is 45 made sufficient to carry the parts to the position shown in Figs. 1 and 7—that is to say, the end of the plunger c^8 is over the cam c^{14} . The parts are so timed that when the plunger c^8 is brought over the cam c^{14} it engages the cam at its low point, and the further rotation of the shaft b^5 causes the cam to force 50 the plunger upward against the tension of the spring c^{11} . This operation acts as a brake, and the resistance offered by the plunger is sufficient to practically bring the shaft b^5 to rest when the plunger reaches and is forced into the notch in the cam shown in Fig. 7. The plunger and its extension c^7 have an axial movement, in addition to the radial movement heretofore described, by reason of the arrangement of the strap or collar c^4 . From this it follows that whatever momentum is in the shaft 55 b^5 when the plunger engages the notch in the

cam c^{14} will be taken up by the spring c^2 , the plunger, shaft, and cam revolving together against the tension of this spring, which is sufficient to overcome the momentum left in the shaft when the plunger engages the notch and brings the shaft to rest without shock or jar. When the bar b^8 is slid to the left in Fig. 2 by means of the arm b^2 , the sliding box 75 is likewise correspondingly slid and the plunger c^8 removed from engagement with the cam c^{14} to the position shown in Fig. 6.

b^{27} represents a pitman connecting the shaft b^5 with the shaft b^{28} in the overhanging arm, 80 by which the needle-bar and its needle are reciprocated.

In Fig. 2, f represents a yoke pivoted to the front side of the machine at f' . A roller f^{80} , connected to the end of the inner arm of said 85 yoke, is arranged in a groove f^{22} on the upper side of a path-cam f^{50} , secured to the vertical shaft e . By this construction the yoke is oscillated on its pivot at predetermined times and to a predetermined extent. f^3 represents 90 a carriage arranged to slide in suitable ways on the arms of the yoke f . f^4 represents an arm connected to the rear end of said frame, the extremity of said arm being formed with a projection or roller arranged in a longitudinal slot f^5 in the free end of a lever f^6 . This lever is pivoted at its opposite end at f^7 to the bed of the machine and midway its ends provided with a roller f^8 , (shown in dotted lines,) 95 arranged in a groove f^9 of the path-cam f^{50} before referred to. By this construction it 100 will be seen that the sliding carriage f^3 is moved forward and back at predetermined times and to predetermined distances, the sliding carriage and supporting-yoke serving 105 as means by which the work-clamp herein- 110 after described is given its several movements of reciprocation and sidewise translation in order to properly position the edge of the buttonhole to the action of the stitch- 115 mechanism.

Referring to Fig. 3, there is shown in side elevation one half of our improved work-clamp, and as the two halves are duplicates of each other a description of one will be sufficient for both, the entire clamp being shown in end elevation in Fig. 1, in top plan view in Fig. 2, and in side elevation in Fig. 4.

Referring to Fig. 3, h represents a pin secured in a vertical position by a screw h' in a cross-bar or casting h^2 on the inner end of the sliding carriage. This pin h , it will be seen, projects both above and below the cross-bar h^2 , and it furnishes a pivot on which is mounted a casting h^3 . h^4 represents an arm 120 projecting from the casting below the cross-bar. h^5 represents an arm projecting from said casting above the cross-bar. h^6 represents one arm of a toggle, one of whose ends is mounted upon a pivot h^7 , carried by the 125 arm h^4 . h^8 represents a short arm secured to the pivot h^7 and provided with a set-screw h^9 , adapted to engage the arm h^4 to limit the 130 movement of the pin h^7 , and consequently the

arm h^6 , or the arms $h^6 h^8$ may be secured together or made integral. h^{10} represents the other arm of the toggle, the knuckle h^{11} of which is formed by the pivotal connection between the two arms $h^6 h^{10}$. h^{12} represents a lever pivoted intermediate its ends on the top of the arm h^5 . The rear end of this lever is pivoted to the arm h^{10} , and at the forward end of this lever is secured the upper jaw h^{13} of the work-clamp. h^{14} represents the lower complementary jaw of the work-clamp and is secured by a screw h^{15} to the casting h^3 . From this construction it will be seen that both the jaws $h^{13} h^{14}$ can be swung simultaneously from the pin h , while the upper jaw h^{13} has a motion to and from the jaw h^{14} for clamping and unclamping the goods, this motion being effected by the toggles composed of the arms $h^{10} h^6$, the work being clamped when the toggle is straightened, as in Fig. 3, by means of the lever a^{21} , and unclamped when the toggle is broken by means of the rock-shaft b^{14} , as shown in Fig. 4 in dotted lines, it being understood, of course, that the work-clamp is made up of two sets of arms, each set being like the pair shown in Fig. 3. The motion of the arms h^{13} away from the jaws h^{14} is simultaneous and in like directions. The swinging motion of each pair of jaws is toward and from each other, the two pairs of jaws being in their nearest position when the buttonhole is being cut, and being thereafter swung on the pins h away from each other in order to spread the buttonhole. The mechanism for spreading the jaws in the present embodiment of our machine consists of a bar carried by each casting h^3 or jaws h^{14} , rigid on said casting, this bar being struck by a movable member. The swinging of the two castings necessitates a simultaneous swinging of the pair of arms carried by each casting. Referring to Figs. 3 and 22, h^{16} represents cam-plates secured to the lower jaws h^{14} with their cam-surfaces facing each other. h^{17} represents a bracket extending up from the cross-bar h^3 between the jaws h^{14} . This bracket at its end supports a rotatable spindle h^{18} . h^{19} represents a pin extending down from said spindle between the cam-plates h^{16} . h^{20} represents a pin extending from said spindle into a loop h^{21} on the upper jaw h^{13} , the pin h^{20} serving to steady the spindle and to move it in one direction, as hereinafter described. h^{22} represents a spring connected with the pin h^{19} , adapted to pull the pin to the left in Fig. 3. h^{23} represents a projection on the bar a^{12} . When this bar is slid to the right in Fig. 3 to throw the cutter-block in the position shown in Fig. 13, the projection passes under the end of the pin h^{19} , as the two clamps are then unseparated; but when the bar is moved to the left the projection h^{23} engages the arm h^{19} and forces it between the cam-plates to separate the clamps and spread the buttonhole, the parts remaining in this position during the sewing operation. When the clamps are drawn up after the sewing operation, the loop

h^{21} engages the pin h^{20} and rocks the spindle to withdraw the pin h^{19} from between the cam-plates, thus allowing the clamps to approach each other.

e represents an upright shaft supported in suitable bearings in the bed of the machine. The shaft is provided with a worm-gear e' , adapted to be driven by a worm e^2 on the shaft b^5 . To this shaft above and below the bed-plate are secured stop-gears $e^3 e^4$, respectively, the stop-gear e^3 being arranged to turn and hold the upper sewing mechanism, while the stop-gear e^4 simultaneously turns and holds the lower sewing mechanism.

The needle-bar r is arranged to turn in suitable bearings r' in the overhanging arm. This needle-bar is centrally cored, as at r^2 , in order to let the needle-thread pass through it to the needle. The needle-bar at its lower end is suitably deflected from a right line, as at r^3 , in order that as the needle-bar is rotated its needle may assume the proper relation in respect to the lower sewing mechanism herein-after described.

s , Fig. 13, represents a turret-cylinder mounted and arranged to turn in a suitable aperture in a bracket in the base of the machine. This turret carries the lower sewing mechanism. Upon the base of the turret and upon the needle-bar are secured complementary stop-gears $e^5 e^6$, adapted for engagement with their complementary gears $e^3 e^4$. As both sets of gears are duplicates of each other and the series act in unison the description of one will suffice for all.

Referring to Figs. 1, 9, and 10, it will be seen that the stop-gears $e^3 e^4$ are composed of a disk e^7 . To one side of this disk is secured a mutilated gear e^8 , while to the opposite side of the disk and to the opposite end of the diameter thereof is secured a differential gear e^9 . The periphery of the disk is mutilated beneath the gear e^8 and above the gear e^9 and is uniform between said gears.

The needle-bar r and the turret s are each provided with a mutilated plate e^{10} to coact with the disk e^7 , the formation of the plates and disks being such that the needle-bar r and turret s are held stationary during predetermined times. Above and below the disk e^{10} are secured a mutilated gear e^{11} and a differential gear e^{12} , corresponding, respectively, to the gears $e^8 e^9$. The cam-surfaces of the coacting plates e^{10} and e^7 are provided, so that the latter can make a partial rotation without effecting a movement of the former, the notches in each of said plates e^7 being to receive the corners of the other plate.

The parts are so constructed that when the complementary gears are in mesh the complementary surfaces of the stop-plates are disengaged, and vice versa. It follows from this that the turret and needle-bar are intermittently rotated by the plates and gears, which we term for convenience "stop-gears."

When the stitching operation begins at one end of the buttonhole, the disk e^7 be-

neath the mutilated portion of the gear e^8 will be in engagement with the complementary stop-face on the disk e^{10} . At the completion of one or more stitches the gear-teeth at the left in Fig. 9 will engage complementary gear-teeth of the turret and needle-bar, thereby giving both parts a partial rotation to turn the upper needle and turret and cause the formation of stitches part way around the end of the buttonhole-slit. Immediately thereafter the stop-plates come to engagement. At this point the sliding frame f^3 is moved forward in order to stitch the side of the buttonhole. At the completion of this movement—to wit, in the vicinity of the eye of the buttonhole—the stop-gears are in the position shown in Fig. 9. As soon as the eye of the buttonhole is reached it is necessary to carry the stitching mechanism around the latter. This is accomplished both by movement of the stitching mechanism and by the swinging movement of the yoke f above referred to. At the proper point the differential gears $e^9 e^{12}$ come into engagement, first moving the needle-bar and turret rapidly and thereafter slowly, the movement being sufficient to carry the sewing mechanism around the eye end of the buttonhole to the opposite side of the buttonhole, at which point the complementary face of the disk e^7 at the right in Fig. 9 comes into engagement with the complementary faces of the disk e^{10} , holding the stitching mechanism stationary. At this point the sliding frame is moved again to the rear to stitch the last side of the buttonhole. When near the completion of the operation, the right-hand gear-teeth of the gear e^8 in Fig. 9 come into engagement with the complementary gear-teeth on the needle-bar and turret, thereby swinging the sewing mechanism around the end of the slit until the stop-faces between the two sets of gear-teeth of the gear e^8 come into engagement with the complementary stop-faces on the needle-bar turret. This presses the parts to the initial position, and the several movements are so timed that at this point the machine is automatically stopped, as heretofore described, and the work unclamped.

It will be noted that the gear-teeth $e^{11} e^{12}$ are at different distances radially from their common support, the teeth $e^8 e^9$ being also at different distances from the axis of their movement. This is for the purpose of causing a differential rotative movement of the stitch-forming mechanism, so that the needles will swing around the small end of the buttonhole-slit more rapidly than around the other end.

The upper sewing mechanism consists of the usual reciprocating needle-bar r and its needle r^4 . The lower sewing mechanism, as I have stated, is mounted in and carried by a turret s and is arranged to be driven by a pitman s' , connected to the shaft b^5 . s^2 represents a bell-crank lever pivoted at its angle

to the turret. One arm of this lever is connected by a ball-and-socket joint to the pitman s' , while the other arm of the lever is connected by a link s^3 to a lever s^4 , which is pivoted at one end to the turret and at its opposite end carries the needle-looper or under-thread carrier s^5 of the lower sewing mechanism. 75

Referring to Fig. 13, it will be seen that the link s^3 , together with one arm of the bell-crank lever s^2 , constitutes a toggle, and that when this toggle is straight the needle s^5 will be at its highest point. The parts are constructed in order to carry the knuckle s^6 still farther to the left to a position corresponding to the position which it occupies to the right in Fig. 13. Supposing the toggle to be straight, then as the knuckle moves to the left the needle s^5 will drop or dip, thereby loosening its thread to form a loop through which the upper needle r^4 can pass. The knuckle then returns to its straight position again, carrying the needle to its highest point, 90 and then the knuckle is carried to the position shown in Fig. 13, bringing the needle to its lowest point. It will thus be seen that the lower needle is not only carried through the fabric, but is also given a dip for the purpose 95 stated.

t represents an arm pivoted at one end of the turret. The free end of this arm (see Figs. 14 and 15) is formed as a bearing t' , in which is loosely arranged a spindle t^2 . To 100 the upper end of this spindle is secured a loop-spreader t^3 .

t^4 represents an arm pivoted at one end of the turret.

t^5 is a link pivoted at one end in ears t^6 in 105 the arm t^4 and at its other end secured to the spindle t^2 .

t^7 is a vertical lip on the arm t^4 , to which is secured a ball t^8 .

t^9 , Fig. 14, represents a link connected at 110 one end to the ball t^8 in a ball-and-socket joint and at its other end by a like joint on the end of the pin t^{10} , carried by the arm s^4 . By this construction it will be seen that the loop-spreader is given a movement of translation and likewise a movement of rotation on the pin t^2 .

The operation of the upper and lower stitch mechanism forming the stitch is shown successively in Figs. 19, 20, and 21. In Fig. 19 115 the lower needle is passed through the loop of the upper needle held by the loop-spreader, while in Fig. 20 the under needle has been projected through the fabric and the upper needle has passed through the loop of the lower needle, the latter being dipped, as heretofore stated. In Fig. 21 the loop-spreader is shown passing through the loop of the upper needle to hold the thread ready for the under needle to pass through the loop of the upper 130 needle, as shown in Fig. 19, it being understood that the lower needle passes through the slot of the buttonhole, while the upper needle penetrates the fabric.

The mechanism for operating the under-thread carrier or "lower needle," as I have termed it, and the loop-spreader are positively connected to the driven parts respectively, 5 being termed either "lever mechanism" or "toggle mechanism." By this positive connection they operate the loop-spreader and the lower needle without the aid or employment of cams or kindred devices, and hence 10 we are enabled to run the machine at a high rate of speed and without noise or a great expenditure of power. The lever mechanism is connected by a universal joint with the operating-shaft, said joint being formed of a ball 15 and socket, whereby the upper portion of the connection is capable of rotating or oscillating relatively to the lower part.

Having thus explained the nature of our invention and described a way of constructing 20 and using the same, though without attempting to set forth all of the forms in which it may be made or all of the modes of its use, what we claim, and desire to secure by Letters Patent, is—

25 1. In a buttonhole-sewing machine, the combination with stitch-forming mechanism, including an upper needle and its bar, and a lower needle and a rotary turret therefor, of an operatively-movable cutter-block mounted 30 on the turret, a buttonhole-cutter adapted to coact with said cutter-block, said cutter and block being movable into and out of the lines of the needle-bar, and means for giving said cutter and block their described operations.

35 2. In a buttonhole-sewing machine, the combination with stitch-forming mechanism including an upper needle and its bar, and a lower needle and a rotary turret therefor, of a cutter mounted on a stationary support, a 40 cutter-block mounted movably on said turret, and automatic mechanism for bodily moving said cutter and block into operative position with respect to the stitch-forming mechanism, whereby the cutting is accomplished without 45 shifting or moving the work.

3. In a buttonhole-sewing machine, the combination of stitch-forming mechanism, a buttonhole-cutter, a rotary turret carrying a 50 part of the said stitch-forming mechanism, and a cutter-block pivotally located upon the turret.

4. In a buttonhole-sewing machine, the combination of stitch-forming mechanism, a 55 turret carrying a part of the said stitch-forming mechanism, a cutter, a cutter-block mounted on the turret and normally in an inoperative position, and means for moving said cutter and block simultaneously into and out of operative position.

60 5. In a buttonhole-sewing machine, the combination of stitch-forming mechanism, a cutter, a turret for carrying a portion of the 65 stitch-forming mechanism, a cutter-block, a support for the cutter-block hinged to the turret, and means for operating the cutter and the cutter-block.

6. In a buttonhole-sewing machine, the

combination of stitch-forming mechanism, a cutter, a turret carrying a portion of the stitch-forming mechanism, a cutter-block 70 movably mounted on the turret, a shaft, and connections between the shaft and the cutter and cutter-block.

7. In a buttonhole-sewing machine, the combination of stitch-forming mechanism including a rotary turret, a cutter, a cutter-block and a throat-plate mounted on said turret, and means for moving the cutter-block and throat-plate into and out of operative position alternately. 75

8. In a buttonhole-sewing machine, the combination of stitch-forming mechanism, a cutter, a turret carrying a portion of the stitch-forming mechanism, a movable support mounted on the turret, and a throat-plate 85 and cutter-block located on said support, and means for actuating said support to move said throat-plate and cutter-block alternately into operative position.

9. In a buttonhole-sewing machine, the 90 combination of stitch-forming mechanism, a turret carrying a portion of said stitch-forming mechanism, a cutter, a throat-plate and a cutter-block connected together and having their operative faces lying in intersecting 95 planes, and a support for said work-plate and cutter-block pivoted upon the turret.

10. In a buttonhole-sewing machine, the combination of a work-clamp, buttonhole-cutting mechanism, a shaft connected to the 100 cutting mechanism, a continuously-rotating wheel loose on the shaft, and having a cam, a two-armed lever adapted to operate the work-clamp, a spring-tensioned clutch, connected to the shaft and disengaged and normally held out of engagement with the said 105 wheel by the two-armed lever, and manually-operated devices for temporarily connecting the two-armed lever with the cam, to cause first the operation of the work-clamp, and secondly, the operation of the cutting mechanism. 110

11. In a buttonhole-sewing machine, the combination with a work-clamp, buttonhole-cutting mechanism, and stitch-forming mechanism, 115 of a shaft, a rotating wheel loose thereon, and clutch mechanism fast thereon for actuating the stitch-forming mechanism, a second shaft, a wheel on said second shaft and having cams fast therewith, a lever 120 adapted to actuate the work-clamp and arranged to be actuated by one of said cams, a spring-tensioned clutch fast on the second shaft adapted to engage the other of said cams but disengaged from and held out of 125 engagement with the said cam by said lever, a second lever adapted to be acted on by one of said cams for engaging and operating the clutch mechanism on the first-mentioned shaft, and manually-controlled devices for 130 engaging the second-mentioned lever with its cam to cause, first, the operation of the work-clamp by the first-mentioned lever, second, the operation of the cutting mechanism by the

- second-mentioned shaft, and third, the operation of the stitch-forming mechanism by connecting the first-mentioned shaft and its wheel through the medium of the second-mentioned lever.
12. In a buttonhole-sewing machine, the combination of stitch-forming mechanism, a rotary turret carrying a portion of the stitch-forming mechanism, buttonhole-cutting mechanism including a movable cutter-block mounted on the turret and a movable cutter, a work-clamp, and mechanism for operating the work-clamp to engage the work, mechanism independent of the stitch-forming mechanism for operating the cutting mechanism to cut a buttonhole-slit while the work is in position for but before the stitching operation, mechanism for setting in motion the stitch-forming mechanism, devices for stopping the said stitch-forming mechanism, and means for operating the clamp to release the work.
13. In a buttonhole-sewing machine, the combination of an upper needle, means for actuating said upper needle, a lower-needle or under-thread carrier adapted to pass through a buttonhole-slit, means for causing the rotation of said upper needle and said under needle or thread carrier, and a toggle for operating the under needle or thread carrier.
14. In a sewing-machine, the combination with an upper needle, an actuating means therefor whereby said needle is caused automatically to travel around the end of a buttonhole-slit, of a turret, means for imparting a rotatory movement to said turret, an under or lower needle supported by said turret, a toggle for actuating said lower or under needle, and means for operating the toggle.
15. In a sewing-machine, the combination with an upper needle, and actuating means to automatically cause the said needle to sew around the end of a buttonhole-slit, of a turret, means for imparting a rotatory movement to said turret, an under or lower needle supported by said turret, toggle-levers for actuating said under or lower needle, one of the toggle-levers being a bell-crank, and means for actuating the bell-crank.
16. In a sewing-machine, the combination with an upper needle, and actuating means to automatically cause the said needle to sew around the end of a buttonhole-slit, of a turret, means for imparting a rotatory movement to said turret, an under or lower needle supported by said turret, a needle-carrier pivoted at its end, toggle-levers one of which is pivoted to the needle-carrier between its ends, and means for actuating the toggles.
17. In a sewing-machine, the combination with an upper needle, and actuating means to automatically cause the said needle to sew around the end of a buttonhole-slit, of a turret, means for imparting a rotatory movement to said turret, a lower or under needle supported by said turret, a pivoted needle-carrier, a support, a toggle pivoted to the support and to the needle-carrier, one of the levers of the toggle being a bell-crank, and mechanism for operating the bell-crank.
18. In a sewing-machine, the combination of an upper needle, means to reciprocate it, means for automatically causing the said needle to sew around the end of a buttonhole-slit, a turret, means for imparting a rotatory movement to said turret, a lower needle, a toggle supported by said turret for reciprocating said lower needle, and means for actuating the toggle.
19. In a buttonhole-sewing machine, a cutter for forming a buttonhole-slit, a work-clamp, and stitch-forming mechanism, said stitch-forming mechanism comprising an upper needle, means to actuate said needle to cause it to sew around the end of a buttonhole-slit, a turret, means for imparting a rotatory movement to said turret, a lower needle adapted to pass through the buttonhole-slit supported by said turret, and means including a toggle for actuating said lower needle.
20. In a buttonhole-sewing machine, a cutter for forming a buttonhole-slit, a work-clamp, and stitch-forming mechanism, said stitch-forming mechanism comprising an upper needle, means to actuate said needle to cause it to sew around the end of a buttonhole-slit, a turret, means for imparting a rotatory movement to said turret, a lower needle adapted to pass through the buttonhole-slit, and supported by said turret, and lever mechanism including a toggle and a bell-crank for actuating said lower needle.
21. In a buttonhole-sewing machine, a cutter for forming a buttonhole-slit, a work-clamp, and stitch-forming mechanism, said stitch-forming mechanism comprising an upper needle, means to actuate said needle to cause it to sew around the end of a buttonhole-slit, a lower needle adapted to pass through the buttonhole-slit, a turret, means for imparting a rotatory movement to said turret, a movable support for said lower needle mounted on said turret, and a toggle for actuating said support, said toggle being constructed and arranged to have its knuckle traverse a path intersecting the line connecting the outer ends of the toggle, whereby said lower needle is caused to dip when it reaches the end of its movement through the said slit, and before it begins its reverse movement.
22. In a sewing-machine, the combination of an upper needle, means to reciprocate it, a turret, means for imparting a simultaneous intermittent rotatory movement to the turret and the upper needle, a lower needle supported on said turret, and means to reciprocate said lower needle, said means comprising a toggle, one member of which is a bell-crank, and means for oscillating the bell-crank.
23. In a sewing-machine, the combination of an upper needle, means to reciprocate it, a turret, means for imparting a simultaneous intermittent rotary movement to the turret and the upper needle, a lower needle mounted on said turret, and means to reciprocate said

- lower needle, said means comprising a pivoted needle-carrier, a toggle pivoted to the turret and to the needle-carrier, and means for oscillating one member of the toggle.
- 5 24. In a buttonhole-sewing machine, a stitch-forming mechanism comprising an upper needle, a lower needle, a loop-spreader, a turret upon which the lower needle and loop-spreader are mounted, means for operating the turret, and a toggle for actuating the loop-spreader.
25. In a sewing-machine, the combination of an upper and a lower needle and their carriers, means for actuating said needles, a loop-spreader, a swinging loop-spreader carrier separate from the lower needle and its carrier, and a toggle for actuating the loop-spreader.
- 15 26. In a sewing-machine, the combination with an upper and a lower needle, carriers for said needles, and actuating mechanism therefor, of a loop-spreader, a pivotal loop-spreader carrier, separate from the lower-needle carrier, a toggle for imparting a movement of translation to the loop-spreader carrier, and a movement of rotation to the loop-spreader and mechanism for actuating the toggle.
- 25 27. In a sewing-machine, the combination of an upper and a lower needle, said lower needle being adapted to pass through a buttonhole-slit, mechanism for actuating said needles, a loop-spreader supported independently of the said needles, and a toggle for actuating the said loop-spreader.
- 35 28. In a sewing-machine, the combination with an upper and a lower needle, said lower needle being adapted to pass through a buttonhole-slit, and mechanism for actuating said needles, of a loop-spreader located permanently below the work, and toggle mechanism for actuating the said loop-spreader.
29. In a buttonhole-sewing machine, the combination of a cutter for making a button-hole-slit, a work-clamp, an upper needle, actuating means for said needle, a lower needle adapted to pass through the buttonhole-slit, actuating means for said lower needle, a loop-spreader, and a toggle for operating said loop-spreader.
- 45 30. In a sewing-machine, the combination with an upper and a lower needle, and means for actuating said upper needle, of a toggle for actuating the lower needle, a loop-spreader, a toggle for actuating the loop-spreader, and connections between the toggles whereby one is actuated by the other.
31. In a buttonhole-sewing machine, the combination of a rotatory upper needle, means for actuating said upper needle, a lower needle, a turret carrying the lower needle, means to rotate the turret in one direction only, a loop-spreader mounted on the turret and toggles for operating the lower needle and the loop-spreader.
- 55 32. In a buttonhole-sewing machine, the combination of a rotatory upper needle, a

lower needle, mechanism for actuating said needles, a rotatory turret carrying the lower needle, a looper mounted on the turret, and a toggle for operating the looper.

70

33. In a buttonhole-sewing machine, stitch-forming mechanism comprising an upper needle, a lower needle, a turret carrying said lower needle, and mechanism for imparting an intermittent rotatory movement always in the same direction to the upper needle and the turret, the last said mechanism comprising coacting disks and coacting mutilated gears.

75

34. In a buttonhole-sewing machine, stitch-forming mechanism comprising an upper needle, a lower needle, a turret, and mechanism for imparting an intermittent differential rotatory movement to the upper needle and the turret, said mechanism including coacting gears each having its teeth farther from its center on one side than on its other side.

80

35. In a buttonhole-sewing machine, stitch-forming mechanism comprising an upper needle, a lower needle, a turret, and mechanism for imparting an intermittent differential rotatory movement to the upper needle and the turret, said mechanism including coacting mutilated gears each having its teeth farther from its center on one side than on the radi- 95 ally opposite side.

36. In a buttonhole-sewing machine, the combination of stitch-forming mechanism and a turret carrying a lower needle, and mechanism for imparting an intermittent rotatory movement to the upper needle and the turret, the last said mechanism comprising a shaft having two mutilated disks each provided with gear-teeth, a mutilated disk and gears on the turret and gears and a mutilated disk on the upper-needle bar.

100

37. A buttonhole-sewing machine, comprising a turret having a mutilated disk, and a gear on each side of the disk, a shaft having a mutilated disk in engagement with the first- 110 mentioned disk, and a mutilated gear on each side of the second-mentioned disk adapted to alternately engage with the mutilated gears of the turret.

110

38. A buttonhole-sewing machine, comprising an upper-needle bar having a mutilated disk and a gear on each side of the disk, and a shaft having a mutilated disk with mutilated gears on each side thereof.

115

39. A buttonhole-sewing machine comprising a needle-carrier having a mutilated eccentric gear, and a driving-shaft having a mutilated eccentric gear to mesh intermittently with the first-mentioned gear, whereby a differential movement is imparted to said 125 needle-bar.

120

40. In a buttonhole-sewing machine, the combination with stitch-forming mechanism of clamping mechanism comprising two clamping members, toggle-levers connected 130 to the outer ends of said members, a lever for throwing the toggle into operative posi-

125

tion, a cam and devices operated by the cam for throwing the toggle into inoperative position.

41. In a buttonhole-sewing machine, stitch-forming mechanism including an upper needle, a lower-thread carrier, and a rotatory turret for said lower-thread carrier, and a throat-plate mounted on said turret and having an aperture to permit of the passage of the buttonhole-cord, said throat-plate also having a slot extending from said aperture to its edge.

42. In a buttonhole-sewing machine, stitch-forming mechanism including an upper needle, a lower-thread carrier, and a rotatory turret for said lower-thread carrier, and a throat-plate mounted on said turret and having an aperture to permit of the passage of the buttonhole-cord, said throat-plate also having a slot for the cord to lie in, and undercut edges for the purpose set forth.

43. In a buttonhole-sewing machine, upper-thread mechanism, under-thread mechanism including a rotary turret, a throat-plate supported on said turret, and mechanism for rocking said throat-plate relatively to the turret for the purpose set forth.

44. In a buttonhole-sewing machine, an upper needle, a lower needle, a turret, a loop-spreader mounted on said turret, mechanism for actuating said loop-spreader to take a loop from one needle and present it to the other, means for operating the upper needle, and lever mechanism including a toggle for operating said lower needle.

45. In a sewing-machine, an upper needle, a lower needle, a turret, a loop-spreader mounted on said turret independently of the needles to take a loop from one needle and present it to the other, means for operating the upper needle, lever mechanism including a toggle for operating said lower needle and connections between the said mechanism and said loop-spreader.

46. In a sewing-machine, an upper needle, a lower needle, a turret, a loop-spreader mounted on said turret independently of the needles to take a loop from one needle and present it to the other, means for operating the upper needle, lever mechanism including a toggle for operating said lower needle, and lever mechanism for operating the said loop-spreader.

47. In a buttonhole-sewing machine, an upper needle, a lower needle adapted to pass through a buttonhole-slit, a pivoted carrier for said lower needle, means for operating the upper needle, a turret for the lower needle to swing it around the end of a buttonhole-slit, and toggle mechanism for operating said lower needle, said mechanism being connected to said lower needle-carrier to move it positively into and out of operative position.

48. In a buttonhole-sewing machine, an upper needle, a lower needle adapted to pass

through a buttonhole-slit, a pivoted carrier for said lower needle, means for operating the upper needle, a turret for the lower needle to swing it around the end of a buttonhole-slit, and mechanism for operating said lower needle, said mechanism comprising a shaft, and positive connections including a toggle between said shaft and said lower-needle carrier whereby said needle is moved positively into and out of operative position.

49. In a buttonhole-sewing machine, an upper needle, a lower needle adapted to pass through a buttonhole-slit, a pivoted carrier for said lower needle, means for operating the upper needle, a turret for the lower needle to swing it around the end of a buttonhole-slit, and mechanism for operating said lower needle, said mechanism comprising a shaft, and positive connections between said shaft and said lower-needle carrier whereby said needle is moved positively into and out of operative position, said connections including a toggle and provisions for permitting a rotatory movement of the needle relatively to the shaft.

50. In a buttonhole-sewing machine, an upper needle, a lower needle adapted to pass through a buttonhole-slit, a pivoted carrier for said lower needle, means for operating the upper needle, a turret for the lower needle to swing it around the end of a buttonhole-slit, a shaft and positive connections between said shaft and said lower-needle carrier whereby the needle is carried into and out of operative position by the shaft, said connections including a toggle and a swivel-joint.

51. In a buttonhole-sewing machine, an upper needle, a lower needle adapted to pass through a buttonhole-slit, a pivoted carrier for said lower needle, means for operating the upper needle, a turret for the lower needle to swing it around the end of a buttonhole-slit, a shaft and positive connections between said shaft and said lower-needle carrier whereby the needle is carried into and out of operative position by the shaft, said connections including a toggle and a ball connected to the toggle and a socket connected to the shaft.

52. In a buttonhole-sewing machine, an upper needle, a lower needle, complementary stitch-forming mechanism, a turret and actuating means therefor, in combination with cutting mechanism comprising an anvil or cutter-block movably mounted on the turret, and a cutter mounted upon a suitable support to which the turret and cutter-block are relatively rotatable.

In testimony whereof we affix our signatures in presence of two witnesses.
